UNITED STATES PATENT OFFICE.

ARTHUR TREVOR DAWSON AND GEORGE THOMAS BUCKHAM, OF WESTMINSTER,
LONDON, ENGLAND, ASSIGNEES TO VICKERS LIMITED, OF WESTMINSTER,
LONDON, ENGLAND.

BREECH MECHANISM OF ORDNANCE.

1,302,517.

Specification of Letters Patent.

Patented May 6, 1919.

Application filed April 13, 1915. Serial No. 21,119.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to the Breech Mechanism of Ordnance, of which

10 the following is a specification.

This invention relates to breech mechanism of the kind comprising two pinions mounted in the breech screw at right angles to one another and driven from a compound 15 pinion on the carrier axis pin or hinge bolt, one of the first mentioned pinions serving to unlock the breech screw and the other to displace it rearwardly in the breech screw carrier before being swung clear of the 20 breech opening by the movement of the carrier about its axis pin or hinge bolt.

The chief object of the invention is to provide improved means for effecting the unlocking and rearward movements of the 25 breech screw.

According to this invention each of the two pinions mounted in the carrier and driven from a pinion on the carrier axis pin or hinge bolt is provided with a crank, one 30 serving to engage with part of a ring which is rotatably supported in the breech screw carrier and in which the breech screw is slidably mounted, and the other to engage with a slot in the breech screw.

35 In order that the said invention may be clearly understood and readily carried into effect, we will describe the same more fully with reference to the accompanying drawings, in which:—

40 Figures 1 and 2 are respectively a sectional rear elevation and a sectional side elevation showing a constructional form of the invention, the parts being shown in the position they occupy when the breech screw is locked.

45 Figs. 3 and 4 are views similar to Figs. 1 and 2 but with the parts in the position they occupy when the breech screw is unlocked and about to be withdrawn, and

50 Figs. 5 and 6 are also similar views with the parts in the position they occupy when the breech screw is fully withdrawn.

55 A is part of the breech screw, B is part of the carrier, and C is the carrier axis pin or

hinge bolt. D represents the crank pinion (herein called the unlocking crank pinion) for effecting the locking and unlocking movements of the breech screw. E represents the crank pinion (herein called the withdrawing pinion) for effecting the withdrawing and forward movements of the breech screw. F represents the ring in which the breech screw is slidably mounted.

60 In the example shown the crank pinions D, E are of the bevel type and are driven from a double bevel pinion C' (or by two separate pinions) carried by the carrier axis pin C, the withdrawing crank pinion E being arranged close to the axis pin, but not immediately behind the breech screw. The 65 crank pinions may be mounted on ball or roller bearings in the carrier. When the breech screw is locked as shown by Figs. 1 and 2, a roller on the unlocking crank pinion D engages with a slot f' in an arm F' forming part of the ring F. A roller on the withdrawing crank pinion E is at this time out of engagement with the slot B' in the breech screw. When the axis pin C is rotated to unlock the breech screw the unlocking crank pinion D is angularly displaced in a clockwise direction (when viewed from the rear) and the crank pinion E is displaced in the opposite direction when viewed from the right hand side. This angular movement of 75 the crank pinion D unlocks the breech screw through the intermediary of the ring F and when this operation has been completed the withdrawing crank pinion E enters the slot B' in the breech screw as shown in Fig. 4 so 80 that continued movement of the carrier axis pin displaces the breech screw into the fully withdrawn position shown in Fig. 6. During this operation the crank pinion D has moved clear of the slot f' into the position 85 shown by Fig. 5, the formation of this slot being such that when the unlocking is completed and the crank pinion E is in position for withdrawing, the crank pinion D runs idly in its groove, thus retaining the breech 90 screw against rotation until it is withdrawn into engagement with the guides on the carrier. Continued movement of the axis pin C then swings the carrier into the open position. The breech screw when fully withdrawn is supported in the carrier, and is 95 retained in position by means of a plunger catch. During the closing and locking of

the breech the above described operations are reversed.

5 The carrier axis pin C may be operated by hand or power through worm gearing at one of its extremities. The hand wheel or motor for operating the breech mechanism may be carried on a non-recoiling part of the mounting as is well understood.

What we claim and desire to secure by 10 Letters Patent of the United States is:—

1. In breech mechanism for ordnance, the combination with the carrier axis pin or hinge bolt, of two pinions thereon, a crank, driven from one of said pinions, for unlocking the breech screw, and a second crank, 15 driven from the other of said pinions, for withdrawing said breech screw, said second crank being arranged to rotate in a vertical plane substantially parallel to a vertical plane containing the axis of the gun and between the said axis and the axis of the said pin or bolt.

2. In breech mechanism for ordnance, the combination with the carrier axis pin or hinge bolt, of two pinions thereon, a crank pinion, gearing with one of said pinions, for unlocking the breech screw and a second crank pinion, gearing with the other of said pinions, for withdrawing said breech screw, 25 said second crank being arranged to rotate in a vertical plane substantially parallel to a vertical plane containing the axis of the gun and between the said axis and the axis of the said pin or bolt.

3. In breech mechanism for ordnance, the combination with the carrier axis pin or hinge bolt, of a member in which the breech screw is slidably mounted, a crank, driven from said axis pin, for engaging with a slot 30 in said member to unlock the breech screw, and a second crank, also driven from said

axis pin, for engaging in a slot in the breech screw to withdraw the breech screw, said second crank being arranged to rotate in a vertical plane substantially parallel to a vertical plane containing the axis of the gun and between the said axis and the axis of the said pin or bolt. 45

4. In breech mechanism for ordnance, the combination with the carrier axis pin or hinge bolt, of a crank driven from said axis pin for unlocking the breech screw, and a second crank arranged with its axis at right angles to that of the first mentioned crank and arranged to rotate in a vertical plane substantially parallel to a vertical plane containing the axis of the gun and between the said axis and the axis of the said pin or bolt, said second crank being also driven from the axis pin for withdrawing the 60 breech screw. 55

5. In breech mechanism for ordnance, the combination with the carrier axis pin or hinge bolt, of two pinions thereon, a crank pinion, gearing with one of said pinions, for unlocking the breech screw, and a second crank pinion arranged with its axis at right angles to that of the first mentioned crank pinion and arranged to rotate in a vertical plane substantially parallel to a vertical plane containing the axis of the gun and between the said axis and the axis of the said pin or bolt, said second crank pinion gearing with the other of said pinions on the axis pin for withdrawing the breech screw. 70 75

In testimony whereof we affix our signatures in the presence of two witnesses.

ARTHUR TREVOR DAWSON.
GEORGE THOMAS BUCKHAM.
